UNITED STATES PATENT OFFICE.

FREDERICK HENRY BRONNER, OF PORTLAND, OREGON, ASSIGNOR TO THE IRWIN-HODSON COMPANY, OF PORTLAND, OREGON, A CORPORATION OF OREGON.

SELF-FEEDING INKING-PAD FOR RUBBER STAMPS AND THE LIKE.

1,321,785.

Specification of Letters Patent.

Patented Nov. 11, 1919.

Application filed March 22, 1917. Serial No. 156,786.

To all whom it may concern:

Be it known that I, FREDERICK H. BRONNER, a citizen of the United States, and a resident of Portland, county of Multnomah, 5 State of Oregon, have invented a certain new and useful Improvement in Self-Feeding Inking-Pads for Rubber Stamps and the like, of which the following is a specification.

10 The object of my invention is to provide an inking pad which is adapted to contain a body of ink sufficient to last for a substantial length of time; furthermore, a pad which may be readily and conveniently 15 charged with ink, that is to say, neither requiring much time nor much attention in this operation.

It is further my object to ink my pad by the process of absorption directed from 20 the bottom of the inking layer upward, instead of from the outer or top face of the pad downward; because the latter mode of applying the ink requires the ink to be spread evenly over the surface, and since the 25 process of absorption is slow, it requires considerable time to properly ink a pad, especially if the same is of some size.

I attain my object by providing my pad with an ink storing cavity, and with means 30 for distributing the ink from such cavity evenly throughout the inking pad. The construction of my device will be readily understood by having reference to the accompanying drawings, in which:

35 Figure 1 shows a sectional perspective, the dotted lines indicating the portion cut away, and the stopper for the inking cavity being also shown, but as removed from the cavity;

40 Fig. 2 shows the grooved face of the ink distributing disk or layer;

Fig. 3 shows a portion of the wire cloth constituting a perforated layer placed on the ink distributing layer; and

45 Fig. 4 is a detail of the stopper for closing the ink holding cavity of my pad.

The base, *a*, is preferably cast in a suitable form, of some gelatinous material. The gelatinous composition which I use is substantially the same as that used for making the rollers of printing presses, which, as well known, consists of "table syrup" approximately 26%, glue 50%, glycerin 22%, and oil of peppermint 2%, the latter ingredient 50 having a tendency to harden the gelatinous

mass, and, furthermore, serves to eliminate the offensive odor of the glue. Said base is made with an ink-holding cavity *b*. *c* is the ink-distributing disk or layer, preferably made of rubber, or other material impervious to the ink, and it is formed as shown in Fig. 2, that is to say, it has an opening *d* at the center corresponding with the cross-section of the ink-holding cavity *b* of the base, and from such cavity radiate 60 ink-feeding grooves *e*, *f*. It is also made with concentric rim-like protrusions *g*, *h*, the longer ink-distributing grooves *f* leading to the circular surface *i* between the rims *g*, *h*, and the shorter ink-feeding grooves *e* leading 65 to the surface *j* within the rim *g*. On the center of the ink-distributing layer *c* is placed a perforated layer *k*, which may be made of any suitable material, but I have found it convenient to make the same of wire interwoven, and in this way obtaining an undulating surface serving to keep the layer of absorbent material *l*, preferably made of felt—which constitutes the working surface 70 of the pad—spaced from the ink-distributing layer *c*, and so permits the latter to properly fulfil its function of evenly distributing the ink from said cavity over the under surface of the disk *l*.

In constructing my pad I first lay the 85 disk of felt in the bottom of the mold, the latter being preferably adapted to cast the base *a* of the shape shown. Then I lay the wire over the center of the disk and cover the wire with the ink-distributing layer or 90 disk *c*, the grooved face of the latter resting on the wire, and then cement or otherwise fasten the disk *c* in place on the felt disk *l*. Preferably the top surfaces of the rims *g*, *h* are cemented to the felt and then serve to 95 keep the gelatinous substance from running into the disk, ink grooves and surfaces between said rims, while molding the base *a*. I then insert a tube where the cavity *b* is to be formed, then pour the gelatinous 100 substance, of which the base is to be formed, into the mold.

m represents the stopper for the ink-holding cavity *b*. When charging the pad the same is inverted and permitted to remain so 105 for a few minutes to give the ink an opportunity to run along the grooves of the ink-distributing layer *c* and so become spread over the under side of the felt layer.

My inking pad should only be used with 110

good quality glycerin rubber stamp ink, the so-called quick-drying inks containing more or less creosote, which is inclined to have a detrimental effect on the pad.

5 I claim:

1. An inking pad comprising a gelatinous base provided with an ink-holding cavity, an ink-distributing layer of material im-

10 pervious to the ink having an opening corresponding with said cavity of the base and having ink-distributing grooves leading therefrom; and a top layer of absorbent material constituting the inking surface, said top layer being integrally amalgamated 15 with said gelatinous base around the circumferential portion of the latter.

2. An inking pad comprising a gelatinous base provided with an ink-holding cavity, an ink-distributing layer of material im-

20 pervious to the ink having an opening corresponding with said cavity of the base and having ink-distributing grooves leading therefrom, a top layer of absorbent material constituting the inking surface, and a per-

25 forated layer between said ink-distributing layer and the underside of said absorbent layer, said top layer being integrally amalgamated with said gelatinous base around the circumferential portion of the latter.

3. An inking pad comprising a gelatinous base provided with an ink-holding cavity, an ink-distributing layer of material im-

30 pervious to the ink having an opening corresponding with said cavity of the base and having ink-distributing grooves leading therefrom, a top layer of absorbent material constituting the inking surface, and a per-

35 forated layer having undulating surfaces between said ink-distributing layer and the under side of said absorbent layer, said top layer being integrally amalgamated with said gelatinous base around the circumferential portion of the latter.

4. An inking pad comprising a gelatinous base provided with an ink-holding cavity, an ink-distributing layer of material im-

45 pervious to the ink having an opening corresponding with said cavity of the base and having ink-distributing grooves leading

50 therefrom, a top layer of absorbent material constituting the inking surface, and a per-

rated layer of woven wire between said ink-distributing layer and the under side of said absorbent layer, said top layer being integrally amalgamated with said gelatinous 55 base around the circumferential portion of the latter.

5. In an inking pad comprising a gelatinous base provided with an ink-holding cavity, and an ink-distributing layer of material im-

60 pervious to the ink having an opening corresponding with said cavity of the base and having ink-distributing grooves leading therefrom, and further provided with peripheral rims inclosing spaces fed 65 by said ink-distributing grooves, said top layer being integrally amalgamated with said gelatinous base around the circumferential portion of the latter.

6. In an inking pad comprising a gelatinous base provided with an ink-holding cavity, an ink-distributing layer of material im-

70 pervious to the ink having an opening corresponding with said cavity of the base and having ink-distributing grooves radiat-

75 ing therefrom, and further provided with peripheral rims inclosing spaces fed by said ink-distributing grooves, a top layer of absorbent material constituting the inking surface, a perforated layer between said ink-distributing layer and the underside of said absorbent layer, said top layer being integrally amalgamated with said gelatinous 80 base around the circumferential portion of the latter.

7. An inking pad comprising a gelatinous base provided with an ink-holding cavity, an ink-distributing layer of material im-

85 pervious to the ink having an opening corresponding with said cavity of the base and having ink-distributing grooves leading

90 therefrom, a top layer of absorbent material constituting the inking surface, a perforated layer between said ink-distributing layer and the under side of said absorbent layer, and a stopper for the cavity of the base, said top layer being integrally amalgamated with said gelatinous base around the circumferential portion of the latter.

8. An article as specified in claim 7, the 100 perforated layer being made of woven wire.

FREDERICK HENRY BRONNER.
